United States Patent Office.

GEORGE DEAL, OF WILMOT, OHIO.

Letters Patent No. 76,307, dated April 7, 1868.

IMPROVEMENT IN HORSE-RAKES.

The Schedule referred to in these Letters Patent and making part of the same.

TO ALL WHOM IT MAY CONCERN:

Be it known that I, GEORGE DEAL, of Wilmot, in the county of Stark, and State of Ohio, have invented an Improvement in Horse-Rakes; and I do hereby declare that the following is a full and exact description thereof, reference being had to the accompanying drawings, making part of this specification—

Figure 1 being a top view of a rake provided with my improvement.

Figure 2, a side elevation thereof.

Figure 3, a longitudinal vertical section of the same, close to one of the thills of the rake.

Like letters designate corresponding parts in all of the figures.

The rake is supported on two wheels, A A, and their axle, B, and is drawn by two thills or shafts, C C. A driver's seat, E, is mounted on the axle B. The rake-teeth L L are secured at the upper end to a roller, D, and are also attached further back to a transverse bar, S, by staples or loops, s s, or otherwise. Thus far the construction presents nothing peculiar.

My invention consists in an improved arrangement of the rake-teeth, and method of adjusting and operating them, by means of the bar S. This bar is located, when the rake-teeth are in working position, directly over the axle B, and is hinged by loops m m; or their equivalent, to the rear ends of adjustable bearing-arms I I. The forward ends of the arms I I are hinged, respectively, to the shafts C C, or, by my improved construction of the rake, to flanges or "angle-irons," G G, which also serve for securing the thills to the axle B. The form and construction of these angle-irons are substantially as shown in the drawings, so as to fulfill the triple purpose of attaching the thills to the axle for mounting the bearing-arms upon, and for sustaining respectively two standards, H H, which are preferably pivoted thereto at p p, and projecting upward through slots or apertures in the bearing-arms I I, are provided with sets of equidistant holes, as shown, into which adjusting-pins h h are inserted for raising or lowering the rake-teeth. The angle-irons extend beneath and embrace the rear ends of the thills, to which they are secured by bolts or otherwise, and they are also bolted to the lower side of the axle B. The adjusting-standards may be otherwise equivalently constructed and arranged. By this means of mounting and adjusting the bar S, the rake-teeth are adjusted directly up and down to vary the pressure on the ground, so that their points or extremities always remain vertically beneath the axle, whereby they adapt themselves to the surface of the ground precisely as the wheels A A rise and descend over the surface. It also enables the roller D to be located forward of the axle sufficiently to balance the rake-teeth, and under the thills, so that it can descend under the axle in raising the teeth out of action from the ground, as indicated by red lines in figs. 2 and 3.

What I claim as my invention, and desire to secure by Letters Patent, is—

The angle-irons G G and the standards H H and bearing-arms I I, to which the bar S is hinged, mounted on said angle-irons, constructed and arranged and applied to the rake substantially as and for the purposes herein specified.

I also claim the combination and arrangement of the hinged bar S, rake-teeth L L, and roller D, so that the said roller balances or nearly balances the rake-teeth, substantially as specified.

The above specification of my improvement in horse-rakes signed by me, this 14th day of October, 1867.

GEORGE DEAL.
